AMUSEMENT MACHINE

Emery Mihalek, Chicago, Ill.

Application May 19, 1954, Serial No. 30,561

Term of patent 14 years

(CL. D34—5)

Fig. 1

Fig. 2

Fig. 3

To all whom it may concern:

Be it known that I, Emery Mihalek, a citizen of the United States, residing at Chicago, in the county of Cook and State of Illinois, have invented a new, original, and ornamental Design for an Amusement Machine, of which the following is a specification, reference being had to the accompanying drawing, forming a part thereof, in which:

I claim:

The ornamental design for an amusement machine, as shown and described.
